CLAIM

The ornamental design for a wheel cover, as shown and described.

DESCRIPTION

FIG. 1 is a front view of a wheel cover showing our new design;

FIG. 2 is a right side view thereof;

FIG. 3 is a top view thereof;

FIG. 4 is a bottom view thereof;

FIG. 5 is a left side view thereof;

FIG. 6 is back view thereof;

FIG. 7 is a section view taken along line 7—7 in FIG. 1;

FIG. 8 is a section view taken along line 8—8 in FIG. 1;

FIG. 9 is a back perspective view thereof;

FIG. 10 is a back perspective view with mounting of fitment shown in broken lines; and,

FIG. 11 is a reduced front view of the wheel cover shown in its position of use.

The broken line showing of environment is for illustrative purposes only and forms no part of the claimed design.
